UNITED STATES PATENT OFFICE

RAYMOND G. MOORE, OF BRIDGEPORT, CONNECTICUT, ASSIGNOR TO THE BASSICK COMPANY, OF BRIDGEPORT, CONNECTICUT

LATCH

Application filed June 22, 1928. Serial No. 287,441.

The present invention relates to an improved latch, particularly for automobile doors and of the type having an inside and an outside operating handle, and in which the outside handle is adapted to be latched against operation by manipulation of the inside handle. The latch is especially adapted for use upon doors of closed cars, being applied to all but one of the doors, and which latter is adapted to be latched from the outside. I particularly propose to provide an outside handle roll-back adapted to operate upon the latch bolt through an intermediate retracting member, and an inside handle roll-back adapted to operate upon the latch bolt through a retracting and latching member cooperatively related to said intermediate member, and which is adapted upon manipulation in one direction to retract the latch bolt through actuation of said intermediate member, and in the other direction to latch said intermediate member against operation by the outside handle roll-back.

Another object is to provide a latch bolt adapted to have free retracting movement in the latched relation of the outside handle, either by manipulation of the inside handle in bolt retracting direction or by pressure applied against the nose end of the bolt, and further to provide a latch construction in which the roll-backs may be placed at any desired points, without changing their main combinative relation, or materially altering the design of the parts, thereby adapting the main parts of the latch to use upon various car doors, in which the positions of the handles are differently arranged; and in the illustrated embodiment, I propose to provide a remote control inside handle roll-back adapted to be placed at any desired point on the door frame.

With the above and other objects in view, an embodiment of the invention is shown in the accompanying drawings, and this embodiment will be hereinafter more fully described with reference thereto, and the invention will be finally pointed out in the claims.

In the drawings:—

50 Fig. 1 is a plan view of an automobile door

lock, according to one embodiment of the invention.

Fig. 2 is a longitudinal sectional view taken along the line 2—2 of Fig. 1.

Fig. 3 is a transverse sectional view taken along the line 3—3 of Fig. 1.

Fig. 4 is a transverse sectional view taken along the line 4—4 of Fig. 1.

Fig. 5 is a detail plan view of the intermediate retracting member employed.

Fig. 6 is a detail plan view of the inside handle retracting and latching member employed.

Fig. 7 is a plan view of the latch, with the cover plates removed, and showing the remote inside handle roll-back connected, the parts being in their normal position, as shown in Fig. 1.

Fig. 8 is a similar view, showing the position of the parts with the latch bolt retracted through operation of the outside handle.

Fig. 9 is a similar view, showing the latch bolt retracted through operation of the inside handle; and

Fig. 10 is a similar view, showing the outside handle latched through operation of the inside handle.

Similar reference characters indicate corresponding parts throughout the several figures of the drawings.

Referring to the drawings and more particularly to Figs. 1 to 6 thereof, the embodiment of the invention shown therein comprises a sheet metal frame or base plate 10 having a face flange 11 bent therefrom at one end, within which a rectangular latch bolt opening 12 is provided. Flanged lip portions 13 and 14, formed of the metal cut from said opening are bent outwardly in parallel spaced relation to each other to form bearings for the latch bolt, the flange 14 being flush with the base plate 10.

The latch bolt comprises a nose portion 15, riveted at 16 to a sheet metal bolt plate or bar 17, guided near its inner end between guide lugs 18 and 19 struck and bent upwardly from the base plate, a coil spring 20, mounted upon the base plate by means of a clip 21, having its end engaged in a recess 22 in the upper edge of the bolt and normally

pressing it to its projected position. In the lower edge of the bolt there is provided an elongated recess 23, for engagement by the intermediate retracting member, presently to be more fully described.

The latch bolt, as well as the other operative parts of the latch, is held in place by means of a cover plate 24, suitably shaped to embrace the latch parts, being spaced from the base by flanges 25 and secured thereto by means of lugs 26 inserted through slots 27 in the base plate and bent over upon its outer surface.

The outside handle roll-back 28 has its hub 29 rotatably engaged in apertures 30 and 31 formed in the base and cover plates adjacent the flange 11, and is adapted to retract the latch bolt through an intermediate retracting slide bar 32 engaging the base plate and provided at its forward end with an upwardly bent flange 33 against which the roll-back engages. A projecting lug 34 is provided at the upper edge of the intermediate retracting bar which engages in the recess 23 of the latch bolt against the rearward wall thereof, the latch bolt spring 20 being adapted to normally press the bolt forwardly against the roll back, thereby limiting the projection of the bolt and yieldably retaining the roll back in its normal position against the flange 11. The elongated recess 23 however, permits free retracting movement of the bolt, through pressure applied to its nose end as in closing the door, independently of the retracting bar 32 and the roll-back.

The intermediate retracting bar is guided in its longitudinal movement at its forward end by engagement of its upper edge, forwardly of the lug 34, with the lower edge of the latch bolt, and by engagement of its lower edge with a guide flange 35 struck and bent from the base plate, and is guided at its rearward end between the guide flange 19 engaging its upper edge, rearwardly of the lug 34, and a similar guide flange 36 bent and struck from the base plate and engaging its lower edge.

In superimposed relation to the retracting bar 32 there is provided a bar 37, also guided in its longitudinal movement by the lower edge of the latch bolt and the flanges 35, 19 and 36, and projecting rearwardly of the base plate, where it is pivotally connected at 38 to one end of a link 39 (Figs. 7 to 10) connected at its other end to the remote control inside handle roll-back 40, placed at any suitable point upon the door frame. This bar 37 is operatively connected to the intermediate retracting bar 32 by means of a lug or flange 41 struck up from the bar 32 and engaging an elongated slot 42 in the bar 37, this connection being such that retracting movement of the bar 37 retracts the intermediate bar 32, thereby retracting the bolt, while retracting movement of the bar 32, through op-

eration of the outside handle roll-back, is permitted independently of the bar 37.

The intermediate retracting bar and the outside handle roll-back are adapted to be locked against movement by movement of the bar 37 in the opposite direction to its retracting movement, and for this purpose a transversely reciprocating stud 43 is mounted in a transverse slot 44 in the base plate, and engages slots 45 and 46 respectively provided in the bars 32 and 37.

The slot 45 is of right-angular shape, its longitudinal portion being relatively elongated and adapted to permit normal retracting movement of the bar 32 in the upper or inoperative position of the stud, (Fig. 8) while its transverse portion is co-extensive with the slot 44 in the base plate and is adapted to latch the bar 32 against movement in the lower or operative position of the stud.

The slot 46 in the bar 37 is of obtuse angular shape, its longitudinal portion being co-extensive with the longitudinal portion of the slot 45 and adapted to permit of retracting movement in the upper position of the stud (Fig. 9), while its angular or camming portion extends to a point longitudinally aligned with the lower end of the slot 44, so that upon movement of the bar 37 in a reverse direction to its normal retracting movement the stud is cammed downwardly in the slot 44, at the same time engaging the transverse portion of the slot 45 of the intermediate retracting bar 32 and latching it against operation, so that retraction of the bolt by means of the outside handle roll-back is prevented (Fig. 10).

In order to unlatch the bar 32 the inside handle is merely turned in retracting direction, the initial movement of the bar 37 in retracting direction camming the stud 43 to its upper or inoperative position in line with the longitudinal portions of the slots 45 and 46, and the continued movement causing retraction of the intermediate retracting bar 32 through abutment of the end of the slot 42 with the lug 41, and consequent retraction of the bolt.

I have illustrated and described a preferred and satisfactory embodiment of the invention, but it will be obvious that changes may be made therein, within the spirit and scope thereof, as defined in the appended claims.

Having thus described my invention, what I claim and desire to secure by Letters Patent is:—

1. In a latch, a latch bolt, retracting means for said bolt including inside and outside manually operable retracting means, an intermediate retracting member cooperatively related to said bolt and interposed between said inside and outside retracting means and said bolt and adapted to be moved in bolt-retracting direction by said retracting

means, a reciprocating member adapted to be actuated by said inside retracting means and connected to said intermediate retracting member to impart retracting movement thereto upon movement in bolt-retracting direction, said intermediate retracting member having a latching slot, said reciprocating member having a camming slot, and transversely movable latching means having 5 transverse movement only cooperatively engaged in said slots and adapted upon movement of said reciprocating member in non-bolt-retracting direction to be cammed by said camming slot into latching relation in 10 said latching slot.

2. In a latch, a latch bolt, retracting means for said bolt including inside and outside manually operable retracting means, an intermediate retracting member cooperatively 15 related to said bolt and interposed between said inside and outside retracting means and said bolt and adapted to be moved in bolt-retracting direction by said retracting means, a reciprocating member adapted to be actuated by said inside retracting means and connected to said intermediate retracting member to impart retracting movement thereto upon movement in bolt-retracting direction, said intermediate retracting member and 20 said reciprocating member adapted to have longitudinal movement in parallel relation to said bolt, said intermediate retracting member having a slot including a longitudinal portion and a latching portion, said reciprocating member having a slot including 25 a longitudinal portion and a camming portion, and transversely movable latching means having transverse movement only cooperatively engaged in said slots and adapted 30 upon movement of said reciprocating member in non-bolt-retracting direction to be cammed by said camming portion into latching relation in said latching portion.

Signed at Bridgeport, in the county of 35 Fairfield, and State of Connecticut, this 9th day of June, 1928.

RAYMOND G. MOORE.
